UNITED STATES PATENT OFFICE.

AUGUSTUS PLINTA, OF ALBANY, NEW YORK.

JOINT FOR SECURING THE ENDS OF RAILWAY-BARS.

Specification of Letters Patent No. 22,031, dated November 9, 1858.

To all whom it may concern:

Be it known that I, AUGUSTUS PLINTA, of the city of Albany, State of New York, have invented a new and useful improvement in 5 the construction of railroad-rails, together with the method of connecting and securing them to each other end with end; and I declare the following specification, with the drawings hereto attached as part of the 10 same, to be a full and perfect description of my invention.

Similar letters in the different figures denote the same parts of the apparatus.

My rail itself is essentially a hollow tube 15 constructed of an arch and reverse arch the arches being circular as shown at A, Figure 1, or elliptical as Fig. 6, the bases of the arches joining each other, or the arches, where a high narrow rail is needed may be 20 separated by a vertical wall, as is shown in Fig. 7, where two circular arches are separated by the walls $x-y$. This tube rests upon, as part of its structure, a foot or flange 25 a, a , of the usual form, being lateral extensions of the lower portions of the reverse arch, and as a face for the tread of car wheels it has a face b projecting from the inner segment of the upper arch, the surface of this face being a slightly curved tangent 30 to the vertical diameter of the circle of the arch, the inner edge of the face rounding off into a lip c ; so that the pressure of a wheel may be within and upon the inner half of the rail, while its flange shall be kept a 35 proper distance from the rail and its appendages.

For the convenience of changing the rail end for end, if desirable, the outer upper segment of the rail may be extended like the 40 inner segment as shown by the dotted lines in Fig. 1.

At each end of the rail, there is a slot G cut through the center of its bottom which extends some inches whose purpose will be 45 described directly.

The rail is to be secured to the ties in the usual way at its flanges by hook headed spikes K .

Having described my rail, I proceed to 50 show the manner by which I secure the ends of the rails to each other. To the cavity of the rail there is fitted a dowel B which may be a solid plug or a tube, of such length as

may be best adapted to strength and convenience in working. The dowel (see Figs. 4 55 and 5) has a recess e, e , cut up into and across its lower periphery fitted to receive the upper portion of a wedge or key D , having a double slope or bevel so as to wedge in a vertical and horizontal direction. This key passes 60 through a slot fitted for it, cut the one half into the end of each contiguous rail (see Fig. 2). The object of this key, it will be seen, is to press up and support the dowel B against the upper surface of the rail cavity so as to 65 keep the upper surface of the rails in line, and transmit the pressure of the load passing over the rail through the arches down to the flanges a, a .

To further strengthen the rails at the point 70 of separation the spaces between the reversed arcs and the flanges have fitted into them washers C and C' through which the key D passes, and on the outer side of the washer C the key D is pierced with slots f, f 75 for two (or more) key shaped spikes E, E , which also pass through square notches in the flange, and then into the crosstie on which the rails rest, so that these keys perform the functions of tightening the key D 80 so keeping the dowel up to its place, holding the washers firmly into their angular spaces keeping the rails in their places longitudinally, and holding the rail down to the tie 85 without a chair.

In order to allow of the removal of one of the rails at any point, without disturbing a series of them, it becomes necessary to move the dowel entirely within the cavity of one of the rails. To do this a pin F passing 90 through the slot G is attached to the dowel, so that by it as a handle moving in the slot the dowel can be slid within the rail leaving the section piece to be lifted out of the line 95 of rails.

The advantage of this form of construction and arrangement of rail is I, its great strength from its arch form the properties of which to resist change of shape by direct pressure or torsion is too well known to require illustration; II, its lightness of structure, the quantity of metal requisite to give strength equal to the I rail being 20 to 25 per cent less; III, the strength and immobility of the dowel in keeping the rails in line, 105 and the simple mode of adjusting any varia-

tion from line; IV, the promptness with which any one of the rails can be taken up and relaid.

What I claim is—

5 The formation of a smooth joint where the ends of hollow rails meet, by inserting therein a plug of iron, or dowel, movable by a pin F, in combination with a transverse

wedge D, washers C, C', and wedge shaped spikes E, E, combined and arranged substantially as described when used without a chair. 10

AUGUSTUS PLINTA.
